Primary Examiner — Alison M Ofstun(74) *Attorney, Agent, or Firm* — Robinson IP Law, PLLC(57) **CLAIM**

The ornamental design for a travel case, as shown and described.

DESCRIPTION

FIG. 1 is a front perspective view of the travel case;

FIG. 2 is a top plan view thereof;

FIG. 3 is a bottom plan view thereof;

FIG. 4 is a left elevational view thereof;

FIG. 5 is a right elevational view thereof;

FIG. 6 is a front elevational view thereof;

FIG. 7 is a rear elevational view thereof; and,

FIG. 8 is an exploded view thereof.

In the drawings, the broken lines illustrate portions of the travel case that form no part of the claimed design.
